(57) **CLAIM**

The ornamental design for an ice bucket lamp, as shown and described.

DESCRIPTION

FIG. 1 is a front, top perspective view of an ice bucket lamp, showing my new design;

FIG. 2 is a rear, bottom perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof; and,

FIG. 8 is a bottom plan view thereof.

The broken lines show portions of the ice bucket lamp that form no part of the claimed Design.

The dashed lines in the figures illustrate portions of the ice bucket lamp that form no part of the claimed design.
